BASIC ESTERS OF POLYARYLACETIC ACIDS
AND PROCESS OF MAKING THE SAME

Karl Miescher, Riehen, near Basel, and Karl Hoffmann, Basel, Switzerland, assignors to the firm of Society of Chemical Industry in Basle, Basel, Switzerland

No Drawing. Application July 6, 1935, Serial No. 30,166. In Switzerland July 12, 1934

16 Claims. (Cl. 260—43)

It is known that many basic esters of tropic acid have an action similar to that of atropin, although weaker. Basic esters of certain other organic acids also exhibit activity, for instance such esters of mandelic acid, atrolactic acid, atro-glyceric acid, benzoic acid and ortho- and meta-oxybenzoic acid. Quite special in this respect is benzilic acid-2,2-dimethyl-3-diethyl-amino-propanol ester; its extraordinary toxic character forbids its use in the clinic (see K. Fromherz, Archiv für experimentelle Pathologie und Pharmakologie, 173 (1933) page 116).

This invention relates to the manufacture of basic esters of polyarylacetic acids, which are compounds of considerably greater compatibility than the said ester of benzilic acid. Thus, for example, the easily accessible dialkylamino-ethanol ester of diphenylacetic acid has an extraordinarily powerful effect on the unstriated muscles. This is unexpected, since hitherto it has been supposed that the presence of an aliphatic hydroxyl group in the acid residue (tropic acid, atrolactic acid, atro-glyceric acid, mandelic acid or benzilic acid) favored the action.

25 The new compounds may be made by acting upon polyarylacetic acids or on a halide, ester or anhydride thereof, in the presence or absence of a condensing agent, with an aminoalkanol substituted at the nitrogen atom, or by the action 30 of a reactive ester of an aminoalkanol, substituted at the nitrogen, on a polyarylacetic acid or a salt thereof, if desired in the presence of an agent which binds acid. Alternatively, polyaryl-acetic acids may be converted into their halogen-35 alkanol esters and the latter caused to react with a secondary amine.

For the production of the halogen alkanol esters the operation is preferably conducted in such a manner that alkylene-halogen-hydrides are caused to react on polyarylacetic acids or the halides, esters or anhydrides thereof, in the presence or absence of condensing agents, or that alkylene-halogen-hydrides or alkylene-dihalides are caused to react on salts of polyarylacetic acids, 45 and replacing in the compounds so obtained any hydroxyl-group which may be present by halogen.

By the addition of an alkyl halide, an alkylene halide, an aryl sulfonic acid ester, a dialkylsulfate, an arylalkyl halide or the like, quaternary ammonium compounds of the bases in question can be produced.

Among reactive esters of aminoalkanols are particularly included esters of these with hydrohalogen acids or arylsulfonic acids or the like.

The new compounds are useful for therapeutic application.

The following examples illustrate the invention, the parts being by weight:—

Example 1

10.6 parts of α,α -diphenylacetic acid are treated with thionyl chloride and the diphenylacetyl chloride thus produced is caused to react with 5.9 parts of diethylaminoethanol at 120° C. The α,α -diphenylacetic acid-2-(diethylamino)-ethanol-esterhydrochloride of the formula

thus produced is recrystallized from ethyl acetate; it melts at 113–114° C. The liberated base is an oil of boiling point 139° C. at 0.005 mm. pressure.

By heating for a short time on the water-bath a solution of 23 parts of this new base with 11 parts of methyl iodide, the methiodide of the α,α -diphenylacetic acid-2-(diethylamino)-ethanol ester soon crystallizes; it melts at 140–141° C. The corresponding methochloride melts at 77–78° C. Instead of diphenylacetyl chloride also diphenyl-acetyl anhydride may be used.

Example 2

42.4 parts of diphenylacetic acid, 41 parts of chloorethyl-diethylamine-hydrochloride, 55 parts of potassium carbonate and 120 parts of acetone are together heated to boiling in a reflux apparatus until the reaction is complete. After cooling, the whole is filtered, the solid matter is washed with acetone and the filtrate and the washings are evaporated to dryness, the residue being extracted with ether. The etheral solution is washed with dilute sodium carbonate solution and dried over potassium carbonate. The oil left on evaporating the ether is fractionated in a high vacuum. The base thus obtained is identical with that described in Example 1.

The same compound may also be obtained by causing equivalent quantities of diphenylacetic acid ethyl-, methyl- or another ester to react with diethylaminoethanol in the heat, and fractionating the reaction product in a vacuum.

Example 3

11.5 parts of diphenylacetic acid chloride are caused to react, in presence of 30 parts of dry pyr-

idine, with 6.5 parts of allylethylaminoethanol of the formula

(boiling at 172° C. at 740 mm. pressure, obtained from allylbromide and ethylaminoethanol). The product of the reaction is extracted with ether 10 and the ethereal solution is washed with sodium carbonate solution and dried over potassium carbonate. The solvent is then eliminated and the oil thus obtained is fractionated in a high vacuum. The diphenylacetic acid-2-allylethylaminoethanol ester of the formula

15 thus formed boils at 197-200° C. at 4 mm. pressure. It forms a hydrochloride of melting point 86° C. which can be recrystallized from acetic ester.

20 Instead of diphenylacetic acid chloride also another halide, for example, diphenylacetic acid bromide, may be used.

Example 4

30 parts of triphenylacetic acid chloride are caused to react with 24 parts of diethylaminoethanol; the reaction mass is extracted with ether, the ethereal solution washed with dilute sodium carbonate solution and dried over potassium carbonate. After evaporation of the solvent the triphenylacetic acid-2-diethylaminoethanol ester 35 of the formula

obtained is distilled in a high vacuum. It boils at 160-170° C. at 0.07 mm. pressure, melts at 45 85-90° C., and forms a hydrochloride of melting point 164-167° C., a methyliodide of melting point 223-225° C., and a methylchloride of melting point 198-199° C.

Example 5

50 23 parts of diphenylacetic acid chloride are caused to react with 8 parts of ethylene chlorhydrine in presence of pyridine. The reaction product is shaken with ether and water; the ethereal solution is dried, the solvent evaporated and the residue fractionated in a vacuum. The 55 diphenylacetic acid-2-chloro-ethanol ester of the formula

65 thus obtained boils at 130-135° C. at 0.01 mm. pressure. 27 parts of this compound are caused to react in the heat with 14 parts of diethylamine; the reaction product is shaken with ether and water; the ethereal solution is dried and the solvent evaporated. The diphenylacetic acid-2-diethylaminoethanol ester thus obtained is identical with the substance described in Example 1 70 and 2.

Instead of ethylene chlorhydrine also other ethylene halogen-hydrides, for example ethylene-bromohydrine, may be used.

In order to obtain the halogen-ethanol ester 75 used as intermediate product one can also pro-

ceed in the following manner: an alkali salt of the diphenylacetic acid is caused to react with an ethylenedihalide as, for instance, ethylene chlorobromide, ethylene bromide or ethylene iodide, or an ethylene halogen-hydrine is caused to react thereupon, and the hydroxyethanol ester thus obtained is treated, for instance, with thionyl chloride.

In similar manner the following compounds may be obtained: diphenylacetic acid-2-methylethylaminoethanol ester (a colorless oil of boiling point 136-138° C. at 0.015 mm. pressure), diphenylacetic acid-2-di-n-butylaminoethanol ester (boiling point 163-165° C. at 0.01 mm. pressure, sulfate melting point 139-140° C.), diphenylacetic acid-2-piperidinoethanol ester (hydrochloride melting point 149-151° C.), diphenylacetic acid-meta-dimethyl aminocyclohexanol ester (viscous oils of boiling point 170-180° C. at 0.035 mm. pressure); the ortho- and para-compounds are also forming viscous oils.

The parent materials hitherto not known for the production of the above compounds are obtained as follows: methylethylaminoethanol (boiling point 146-148° C. at 734 mm. pressure) 25 from ethylaminoethanol and formaldehyde in presence of formic acid; m-dimethyl aminocyclohexanol (boiling point 101-104° C. at 6 mm. pressure) by methylating m-aminocyclohexanol of melting point 73° C., the latter being obtained by 30 reducing m-acetylaminophenol with a catalyst and by subsequent saponification. The ortho- or para-compounds are obtained in an analogous manner.

What we claim is:—

1. The basic esters of the formula

40 wherein Y represents a member of the group consisting of a dialkylamine, an alkyl-allylamine and a piperidine ring, R represents a member of the group consisting of hydrogen and phenyl, and A represents a member of the group consisting of an unsubstituted alkylene chain and a cyclohexane ring, which substances are soluble in organic solvents and insoluble in water, forming with acids water-soluble salts of strong antispasmodic 45 action.

2. The basic esters of the formula

55 wherein Y represents a member of the group consisting of a dialkylamine, an alkyl-allylamine and a piperidine ring, and R represents a member of the group consisting of hydrogen and phenyl, which substances are soluble in organic solvents and insoluble in water, forming with acids water-soluble salts of strong antispasmodic 60 action.

3. The basic esters of the formula

65 wherein Y represents a member of the group consisting of a dialkylamine, an alkyl-allylamine and a piperidine ring, which substances are soluble in organic solvents and insoluble in water, forming with acids water-soluble salts of strong antispasmodic 70 action.

4. The basic ester of the formula

5 which substance is a colorless oil soluble in organic solvents and insoluble in water, forming with acids water-soluble salts of strong antispasmodic action.

10 5. The basic ester of the formula

15 which substance is a colorless oil soluble in organic solvents and insoluble in water, forming with acids water-soluble salts of strong antispasmodic action.

20 6. The basic esters of the formula

25 wherein R₁ and R₂ stand for alkyl, and A stands for a cyclohexane ring, which substances are soluble in organic solvents and insoluble in water, forming with acids water-soluble salts of strong antispasmodic action.

30 7. The basic esters of the formula

35 wherein A stands for a cyclohexane ring, which substances are soluble in organic solvents and insoluble in water, forming with acids water-soluble salts of strong antispasmodic action.

40 8. The basic ester of the formula

45 which substance is a colorless oil soluble in organic solvents and insoluble in water, forming with acids water-soluble salts of strong antispasmodic action.

50 9. A process for the manufacture of basic esters, which comprises causing products of the formula

55 wherein R represents a member of the group consisting of hydrogen and phenyl and x represents a member of the group consisting of oxyalkyl and halogen, to react with products of the formula

60 wherein A represents a member of the group consisting of an unsubstituted alkylene chain and a cyclohexane ring, and y represents a member of the group consisting of a dialkylamine, an alkyl-allylamine and a piperidine ring.

65 10. A process for the manufacture of basic esters, which comprises causing products of the formula

wherein R represents a member of the group consisting of hydrogen and phenyl and x represents a member of the group consisting of oxyalkyl and halogen, to react with products of the formula

5 wherein y represents a member of the group consisting of a dialkylamine, an alkyl-allylamine and a piperidine ring.

10 11. A process for the manufacture of basic esters, which comprises causing products of the formula

15 wherein x represents a member of the group consisting of oxyalkyl and halogen, to react with products of the formula

20 wherein y represents a member of the group consisting of a dialkylamine, an alkyl-allylamine and a piperidine ring.

25 12. A process for the manufacture of a basic ester, which consists in causing products of the formula

30 wherein x stands for a member selected from the group consisting of oxyalkyl and halogen, to react with the product of the formula

35 13. A process for the manufacture of a basic ester, which consists in causing products of the formula

40 wherein x stands for a member selected from the group consisting of oxyalkyl and halogen, to react with the product of the formula

45 14. A process for the manufacture of basic esters, which consists in causing products of the formula

50 wherein x stands for a member selected from the group consisting of oxyalkyl and halogen, to react with products of the formula

55 wherein A stands for a cyclohexane ring and R₁ and R₂ stand for alkyl.

60 15. A process for the manufacture of basic esters, which consists in causing products of the formula

wherein α stands for a member selected from the group consisting of oxyalkyl and halogen, to react with products of the formula

5

wherein A stands for a cyclohexane ring.

16. A process for the manufacture of a basic ester, which consists in causing products of the formula

wherein α stands for a member selected from the group consisting of oxyalkyl and halogen, to react with a product of the formula

5
